UNITED STATES PATENT OFFICE.

WILLIAM GEORGE HAROLD FINCH, OF NEW YORK, N. Y.

WIRELESS RECEIVING AND RECORDING APPARATUS.

1,331,098.

Specification of Letters Patent. Patented Feb. 17, 1920.

Application filed July 2, 1919. Serial No. 308,089.

To all whom it may concern:

Be it known that I, WILLIAM G. H. FINCH, a citizen of the United States, residing at New York, in the county of New York and State of New York, have invented certain new and useful Improvements in Wireless Receiving and Recording Apparatus; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in wireless telegraphic recording apparatus, and consists of a simple and efficient means of this character which will record wireless messages for any distances for which the apparatus is designed.

The invention consists of a simple and efficient apparatus of this nature, having various details of construction, combination and arrangement of parts which will be hereinafter fully described and then specifically defined in the appended claim.

My invention is illustrated in the accompanying drawings which, with the letters of reference marked thereon, form a part of this application, and in which:

Figure 1 is a central sectional view through the receiving and recording apparatus, and

Fig. 2 is a diagrammatic view of a wireless telegraph receiving circuit, in connection with which the apparatus is used.

Reference now being had to the details of the drawings by letters:

A designates a 3000 ohm receiver mounted upon a suitable support B, and C is a dia-

phragm forming a part of the receiver and which has a contact point D projecting centrally therefrom and through an opening 45 in the receiver. A binding post E mounted upon the base F has electrical connections H with the diaphragm, and other binding posts, designated respectively by letters I and K, have electrical connections with the 50 windings of the electro-magnet receiver. A post L rising from the base and to which a binding post N is connected, supports an adjustable contact point O.

In operation, when the apparatus is connected in a detector circuit, as shown in Fig. 2 of the drawings, incoming signals or electrical impulses, will cause the electro-magnet of the receiver to become energized and the diaphragm being attracted thereby, will 60 cause the contacts D and O to make and break according to the length of the received impulses, thereby opening and closing the local relay circuit and causing the armature of the relay to make and break circuit, according to the length of received impulses upon a tape recorder.

By the provision of a switch in the relay circuit the latter may be opened when not in use, thereby saving battery energy. 70

What I claim to be new is:

An apparatus for recording wireless messages comprising an electro-magnet receiver including a supporting member with a flanged shell fixed thereto, and a yielding 75 diaphragm with a circumferential flange, having threaded connection with the circumference of the shell, a contact point projecting centrally from said diaphragm, an adjusting screw and mounting therefor, said 80 screw having a contracted contact point.

In testimony whereof I hereunto affix my signature.

WILLIAM GEORGE HAROLD FINCH.
